Robert Morrison

United States Patent Office.

ROBERT MORRISON, OF NEW YORK, N. Y.

Letters Patent No. 98,515, dated January 4, 1870.

IMPROVEMENT IN WRENCHES.

The Schedule referred to in these Letters Patent and making part of the same.

To all whom it may concern:

Be it known that I, ROBERT MORRISON, of the city, county, and State of New York, have invented a certain new and useful Adjustable Pipe-Wrench.

My invention relates to the novel combination and use of a compression-cam attached to the handle, and an extension-screw, by means of which a proper bearing-connection may readily be maintained between the cam and the jaws of the wrench; and I do hereby declare that the following specification, taken in connection with the drawings furnished, and forming a part of the same, is a true, clear, and exact description thereof.

Reference being had to the drawings—

Figure 1 represents, in side view, one of my improved wrenches.

A represents the compression-cam. It is attached to a metallic shank, which passes longitudinally through, and forms, in fact, a part of the handle.

B represents the connecting-pin, which unites the handle of the wrench to the slide-bar. The cam A is slotted to receive a tenon on the slide-bar, and the pin B is fitted closely to the shank and loosely to the tenon, so as to admit of a free swinging movement.

C is the slide-bar, to which the stationary or outer-jaw is attached, or of which it may be a part.

D is the movable jaw, fitted to slide upon the bar C.

E is the cam-block, fitted, like D, to slide upon the bar.

F is a double-threaded screw, tapped into and connecting the cam-block E to jaw D, and is so arranged that by turning the screw, these two parts are moved to or from each other.

Figure 2 represents the same as fig. 1, top view.

Figure 3 represents the jaws of the wrench, with a block, G, inserted, so as to adapt it to ordinary uses.

This block may be secured in position in any well-known manner, or the stationary jaw attached to the shank may be made with a square face, as my improvement, while more especially adapted to pipe-wrenches, is also applicable to other kinds.

The operation of my wrench is obvious. By turning the screw, the jaws may be made to properly engage with the pipe. By turning the wrench, the cam is brought to bear upon the cam-block, and the requisite degree of compression is produced.

Having thus described my invention,

I claim as new, and desire to secure by Letters Patent—

The improved adjustable wrench herein described, provided with a cam-block and movable jaw, connected and adjusted by the screw F, and arranged to operate in combination with a cam and slide-bar, substantially as described.

ROBERT MORRISON.
